UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

STRIPING MECHANISM FOR AUTOMATIC WEFT-REPLENISHING LOOMS.

1,366,940.

Specification of Letters Patent.

Patented Feb. 1, 1921.

Application filed June 2, 1920. Serial No. 385,916.

To all whom it may concern:

Be it known that I, ALONZO E. RHOADES, of Hopedale, in the county of Worcester and State of Massachusetts, have invented new and Improved Striping Mechanism for Automatic Weft-Replenishing Looms, of which the following is a specification.

The object of the present invention is to automatically change the weft in a weft replenishing loom for the purpose of weaving the fabric with crosswise extending stripes of different quality, color, or appearance from the body of the fabric. More particularly the improved striping mechanism is used in automatic weft replenishing terry looms for weaving the character of towels commonly known as "Turkish" so that stripes near the ends of each towel may present a different color from the remainder 20 of the towel.

The improvements are illustrated in the accompanying drawings, wherein—

Figure 1, is a side view of so much of an automatic weft replenishing terry loom as is necessary for an understanding of the present invention. Fig. 2 is a plan view (enlarged) and Fig. 3 is a front view (enlarged) of the resetting mechanism.

Reference numerals indicate known parts, 30 and reference letters indicate the new parts.

The loom having the present improvements is an automatic weft replenishing loom of the well known Northrop type the characteristics of which are disclosed in 35 United States Letters Patent of Northrop No. 529,940, November 27, 1894, and the change of weft is initiated by a weft detector which indicates the need for a fresh supply of weft, such detector being preferably 40 of the "feeler" type which causes a change of weft before the running weft is entirely exhausted. Such feeler mechanisms are well known and the accompanying drawings illustrate one similar to that disclosed in 45 United States Letters Patent of Wood and Northrop No. 789,471, May 9, 1905.

This feeler mechanism includes a feeler finger 1, which enters the shuttle and contacts with the weft therein, and a feeler 50 finger 2, pivotally mounted on the finger 1. This finger 2, when the weft approaches exhaustion contacts a datum surface, such as the front face of the shuttle, and is thereby abnormally positioned by swinging on the 55 primary feeler. The finger 2 has a for-

wardly extending actuator 3 which, as the result of the abnormal position of the feeler is brought into acting position immediately behind a lever 4, so that when the finger is moved forwardly by the frontward push of 60 the weft carrier in the shuttle, the actuator encounters the lever and the lever is moved forwardly. The result, as set forth in said Wood and Northrop patent, is to cause the usual weft hammer to engage operatively a 65 transmitter 5 which is pivoted at its forward end to a reciprocating crank arm 6, fast on the starting shaft of the weft replenishing mechanism such shaft being shown at *d'* in said Wood and Northrop 70 Patent No. 789,471 and in said Northrop Patent No. 529,940. As the result of this engagement and its subsequent forward movement the weft hammer acts through the transmitter 5, and the crank arm 6 to rock 75 the starting shaft thereby putting into action the weft transerrer by means of which the running weft carrier is ejected and a fresh weft carrier is transferred from the battery or magazine into the shuttle. This 80 mode of operation and the mechanism effecting it are disclosed in said Northrop Patent No. 529,940, and are now well known. (The crank arm 6, is a known part of the weft replenishing mechanism, and serves to indicate 85 the presence of such mechanism.) The feeler mechanism of the Wood and Northrop Patent No. 789,471 (which is incorporated in the loom equipped with the present improvements) is representative of a well 90 known type of feeler mechanism and other detector mechanism could be employed.

The loom having the present improvements has also the terry mechanism for weaving Turkish towels which is set forth 95 in my United States Letters Patent No. 1,322,730, November 25, 1919. Of the mechanism set forth in that patent, only a portion of the pattern mechanism is here illustrated. Fig. 1 of the accompanying drawings shows the pattern cam wheel 7 and certain of the cams 8, 9, 10, and 11, thereof which by their action on intervening mechanism automatically control the terry-motion, the terry-let-off and the let-back as set 100 forth in said Patent No. 1,322,730. Also, as set forth in said patent the pattern wheel 7 is rotated step by step, each forward step occurring after a predetermined number of 105 picks.

Now, in accordance with the present invention, the pattern wheel is equipped with additional cams which at the proper times act upon a controlling mechanism which 5 sets into action the train of weft replenishing mechanism so that the running weft carrier is ejected and a fresh weft carrier is transferred from the magazine into the shuttle. In the specific organization illustrated, this controlling mechanism (when 10 put into action by one of the cams on the pattern wheel) acts to depress the actuator 3 of the feeler finger 2, so that when the finger 1, is moved forwardly the weft replenishing mechanism is brought into action through the same train of mechanism as when the running weft approaches the critical stage of exhaustion. In other words, 15 the pattern cam acts through the controlling mechanism upon the detector which is abnormally positioned and through the detector mechanism upon the weft replenishing mechanism. The loom thus has weft replenishing mechanism which responds to the 20 call both of the usual detector and also of the pattern mechanism.

As shown in Fig. 1, the pattern cam wheel carries two cam blocks A and B which are independently adjustable circumferentially 30 upon the pattern wheel in the same way as the cam blocks are adjustable which carry the cams which control the terry-motion, such adjustments being set forth in said Patent No. 1,322,730.

35 The cam block A has two cams *a* and *b*, and the cam block B has two cams *c* and *d*. By means of one set of those cams a contrasting stripe is woven near one end of a towel, and by means of the other set of cams 40 a stripe is woven near the other end of the towel. The two cam blocks are independently adjustable so that the position of the stripes with respect to the ends of the towels can be adjusted and also in order to 45 conform to the adjustment of the terry-motion controlling cams 8, 9, 10 and 11, so that the contrasting stripes may be coördinated with the stripes of plain and terry weave as desired.

50 Immediately coöperating with the cams *a*, *b*, *c* and *d*, is a controller C consisting of a lever which is pivoted at *e*, to a stationary bracket *f*, carried by the loom frame.

The rear end of the controller C is beveled at *g*, and the meeting faces of the cams *a*, *b*, *c* and *d*, are correspondingly beveled so that when one of these cams in the forward rotation of the pattern wheel encounters the controller, the rear end of the controller 55 is swung downwardly without shock. This downward swing of the rear end of the controller is against the pull of a spring D which acts to restore the controller to its normal position of rest, shown in Fig. 1, 60 after each cam has passed the rear end of

the controller. As shown in Fig. 1, the rear end of the controller projects upwardly at *h*, so that it may enter between each pair of cams *a*, and *b*, and *c* and *d*, and so be restored to its normal position of rest after 70 each cam has acted. The front arm E of the controller extends forwardly to a position above the feeler and is arched upwardly, as shown in Fig. 1, so as to pass above the lay.

75 At its forward end, this arm of the controller extends forwardly and horizontally to constitute a latch F which normally engages a cam bar G adjacent the finger 2, and restrains the same from rearward movement. This cam bar is acted upon by a spring H which tends to move it rearwardly but this rearward movement is normally restrained by the latch F. The rear end of the cam bar G is notched as shown in Fig. 1 80 where it is engaged by the latch. The cam bar has a longitudinal inclined front cam slot *i*, into which enters a stationary horizontally extending pin *j*, and it likewise has a rear longitudinally extending cam slot *k*, 85 into which enters a stationary horizontal pin *l*. The rear under side of the cam bar is shaped to constitute a cam I, which is directly over the forward end of the actuator 3 of the finger 2.

90 Now, referring to Fig. 1, assume that in the rotation of the pattern wheel 7 the cam *a*, encounters the rear end of the controller C thereby depressing the rear end, the result is that the latch F at the forward end of the controller is lifted above the cam bar G, so that the cam bar is free from restraint. Thereupon the cam bar is moved rearwardly by the spring H and as the result of the action of the slots *i* and *k*, upon the pins *j* and 95 *l*, the rear cam face I of the cam bar is moved downwardly thereby encountering the forward end of the actuator 3 and moving said actuator downwardly behind the lever 4 of the feeler mechanism. Then, 100 when the finger 1 is moved forwardly by the forward push of the weft carrier the lever 4 is moved forwardly in just the same way as if the running weft were approaching exhaustion. The consequence is that 115 the weft replenishing mechanism is put into action, and the working weft carrier is ejected and a fresh weft carrier is transferred from the magazine into the shuttle.

120 The same forward step of the pattern wheel which results in the swing of the controller C by the cam *a*, carries said cam forwardly beyond the upward projection *h*, of the controller and the spring D then restores the controller to its normal position 125 of rest, but at this time the cam bar is at its rearward position with its notch back of the front end of the latch F. It is necessary, therefore, after the weft replenishing mechanism has been started into action to reset 130

the cam bar so that it may be locked again in its forward position by the latch F. The resetting mechanism is controlled by the crank arm 6. It is through the movement 5 of the crank arm 6 that the cam bar G is restored to its forward position of rest. At its forward end the cam bar is connected with the outer arm J of a lever which is pivoted at m to a stationary bracket n, 10 fastened to the breast beam 12. The inner arm L of the lever has an upwardly projecting stud o, which extends through a horizontal slot p in a link M. This link at its forward end is pivoted at q, to the outer 15 arm N of a lever which is pivoted at r to the stationary bracket n. The inner arm O of the lever extends in front of the crank arm 6.

In the normal position of rest of the cam 20 bar the stud o is at the rear end of the slot p, as shown in Fig. 2. When the cam bar is moved rearwardly by its spring H the stud o, moves forwardly in the slot p but not far enough forward to have any tendency to 25 swing the lever N, O, on its pivot. As already explained, this rearward movement of the cam bar is followed by the forward movement of the crank arm 6, owing to the timing of the weft hammer and of the pattern mechanism. This forward movement 30 does not occur until after the controller C has been released by the passage of one of its actuating cams (such as a) beyond its projection h, and consequently not until 35 after the controller has been restored to its normal position of rest. As the crank arm 6 moves forward it encounters the arm O thus moving said arm forwardly and consequently moving the arm N and link M 40 rearwardly. The consequence is that the link M forces the stud o, and the lever L rearwardly thereby swinging the lever arm J forwardly and hence moving the cam bar G forwardly. This forward movement of 45 the cam bar brings the locking shoulder s of its notch forward of the latch F. Then when the crank arm 6 is restored to its normal position of rest by the usual spring, such as shown at c²⁰, in United States Letters Patent of Northrop No. 529,943, November 27, 1894, the lever N, O, is released and the spring H again brings the cam bar into locking engagement with the latch F. The lever N, O, and the link M might be 55 restored to the position shown in Fig. 2, by a spring, but this is unnecessary because if the said lever and link were left in the position to which they were moved by the forward movement of the crank arm 6, there 60 would be no interference with subsequent action since they would then be moved to the position shown in Fig. 2 when the cam bar next moved rearwardly.

Therefore, whenever one of the cams a, b, 65 c or d, acts upon the controller C there is

an injection of the running weft carrier and the insertion of a fresh weft carrier. In order to coördinate this change of weft carriers to the requirements of a towel loom the weaver arranges the weft carriers in the 70 magazine in proper sequence. Assume that the body of the towel is to be woven with a white weft, and the stripes are to be woven with a blue weft. In that event sufficient weft carriers with white weft are placed 75 consecutively in the magazine to weave the body of the towel. This will require (as an illustration of a specific instance) the consumption of the weft carried by two full weft carriers and approximately half of the weft on 80 a third weft carrier. In such case the three white weft carriers will be placed in the magazine in a group one after the other. After the loom has been running the first of 85 these weft carriers will be inserted into the shuttle as the result of the action of the pattern mechanism. The two following weft carriers will be inserted as the result of the normal action of the detector mechanism. As the weft on the third weft carrier will 90 be approximately only half consumed there is a wide margin of safety to compensate for any ordinary deviation in the quantity of weft on the weft carriers, so that there will always be enough of the white weft to weave 95 the body of the towel. In the event that a weft thread breaks or should run out before the feeler mechanism acts, the loom will automatically stop by the weft fork as customary in feeler looms of the Northrop 100 type, as illustrated for example, in the aforesaid patent of Wood and Northrop. The weaver then sees to it that the weft is properly supplied before restarting the loom.

Following the group of three white weft carriers the weaver places in the magazine a weft carrier wound with blue weft. As the blue stripe is ordinarily relatively narrow the weft carrier when full will have 110 more than enough weft for the blue stripe so that there is no danger of the normal action of the feeler mechanism during the weaving of the blue stripe. At the completion of the blue stripe, the pattern controlled weft replenishment takes place and the blue weft carrier is ejected and a weft carrier carrying white thread is then inserted. Commonly the colored stripes are 115 near the ends of the towels, and accordingly the cam blocks A and B are near together as shown in Fig. 1. In the position of the parts shown in Fig. 1 the body of the towel is nearing completion. The action of the first cam a is to eject the last white weft carrier of the group of three from the shuttle and to insert a blue weft carrier. A blue stripe is woven until the next cam b acts 120 upon the controller C. Then the blue weft carrier is ejected and a white weft carrier is 125 130

inserted. With the arrangement of the cams illustrated, this weft carrier wound with white thread continues in use until the leading end of the next towel has been begun, and during this interval the weaving is plain or terry or both depending upon the disposition of the terry motion cams, such as indicated at 8, 9, 10, and 11. At the proper time in order that there may be a blue stripe at the beginning of the next towel, the cam *c* acts upon the controller *C* and a second blue weft carrier is inserted so that a blue stripe is woven until the cam *d* acts upon the controller with the result that the blue weft carrier is ejected and the first of the next group of three white weft carriers is inserted.

The extent of weaving between the action of the cams *b* and *c* is insufficient to consume all of the weft on a filled weft carrier so that there is no danger of adversely affecting the prearranged disposition of the weft carriers in the magazine through the normal action of the feeler mechanism during this period.

With the cam arrangement illustrated on the pattern mechanism the weft carriers would be arranged by the weaver in the magazine in the sequence of three white weft carriers, one blue weft carrier, one white weft carrier, and one blue weft carrier, this sequence being then repeated.

The plane of the cams *a*, *b*, *c*, and *d*, on the pattern wheel is such that they do not act upon the levers governed by the cams 8, 9, 10, and 11, and the corresponding position of the rear end of the controller *C* is such that it is not acted upon by any of the cams 8, 9, 10 and 11.

40 A stationary stop pin *P* limits the upward movement of the rear end of the controller *C*.

The controller *C* is below the pattern wheel whereas the levers controlled by the terry-motion governing cams are above the pattern wheel. Accordingly, the cams which govern the controller *C* are located on the pattern wheel remote from the terry motion governing cams so that the two sets of cams can be independently adjusted on the pattern wheel without interference.

I claim—

1. A weft replenishing loom having a weft replenishing mechanism comprising a reciprocating part, as 6; a feeler mechanism having a feeler finger which is positioned to initiate the action of the weft replenishing mechanism when the running weft approaches exhaustion; a normally idle cam bar positioned above said feeler finger, said cam bar having cam slots; fixed pins entering said cam slots; a spring acting upon said cam bar to cause it to engage said feeler finger and move it to its acting position; a pattern mechanism having a series of cams;

a controller acted upon and moved by said cams, said controller having a latch which normally engages said cam bar and holds it in idle position out of reach of said feeler finger, in combination with a resetting mechanism for the cam bar including a lever connected with the cam bar, a second lever extending in front of said reciprocating part of the replenishing mechanism, and a link connecting said two levers, said link having a longitudinally extending slot, and said lever connected with the cam bar having a stud extending into said slot. 70 75

2. A weft replenishing loom having, in combination, a feeler mechanism having a feeler finger which is positioned to initiate the action of the weft replenishing mechanism when the running weft approaches exhaustion; a normally idle cam bar positioned above said feeler finger, said cam bar having cam slots; fixed pins entering said cam slots; a spring acting upon said cam bar to cause it to engage said feeler finger and move it to its acting position; a pattern mechanism having a series of cams; and a controller acted upon and moved by said cams, said controller having a latch which normally engages said cam bar and holds it in idle position out of reach of said feeler finger. 90 95

3. A weft replenishing loom having, in combination, a detector which is positioned to initiate the action of the weft replenishing mechanism when the weft needs to be replenished; a normally idle bar positioned adjacent said detector; a spring acting upon said bar to cause it to engage said detector and move it to its acting position; a pattern mechanism having a series of cams; and a controller acted upon and moved by said cams, said controller having a latch which normally engages said cam bar and holds it in idle position out of reach of said detector. 100 105

4. A weft replenishing loom having weft replenishing mechanism including a reciprocating part, as 6, a pattern controlled cam bar and a spring moving said cam bar rearwardly, in combination with a resetting mechanism for the cam bar including a lever connected with the cam bar, a second lever extending in front of said reciprocating part, and a link connecting said two levers, said link having a longitudinally extending slot, and said lever connected with the cam bar having a stud extending into said slot. 110 120

5. A weft replenishing terry loom having, in combination, weft replenishing mechanism, a detector which ascertains the need for weft replenishment, a pattern mechanism which governs the terry-motion, and connecting mechanisms between the detector and the pattern mechanism on the one hand and the replenishing mechanism on the other hand, whereby the weft replenishment 125 130

is controlled both by the detector and by the pattern mechanism.

6. A weft replenishing loom having, in combination, weft replenishing mechanism, 5 a detector which is abnormally positioned when the weft needs replenishment, operative connections between the detector and weft replenishing mechanism whereby the weft is changed as the result of the abnormal 10 position of the detector, a pattern mechanism, and operative connections between the pattern mechanism and the detector so that the detector is abnormally positioned to initiate the action of the weft replenishing 15 mechanism at the call of the pattern mechanism.

7. A weft replenishing loom having, in combination, weft replenishing mechanism, a feeler mechanism which sets the weft re-

plenishing mechanism into action on the approaching exhaustion of the running weft, and a pattern mechanism operatively connected with the replenishing mechanism whereby the weft is also changed at the call of the pattern mechanism. 20

8. A weft replenishing loom having, in combination, weft replenishing mechanism, a detector which ascertains the need for weft replenishment, a pattern mechanism, connecting mechanisms between the detector and the pattern mechanism on the one hand and the replenishing mechanism on the other hand, whereby the weft replenishment is controlled both by the detector and by the pattern mechanism. 25 30 35

In witness whereof I have hereunto signed my name.

ALONZO E. RHOADES.
